DISPENSING DEVICE

William Friedman, New York, and Benjamin Lindner, Larchmont, N. Y.; said Friedman assignor to said Lindner

Application December 27, 1932, Serial No. 649,024

11 Claims. (Cl. 128—234)

This invention relates to dispensing devices, and more particularly to that type of dispensing devices wherein the material to be dispensed is extruded as required from the container.

The objects of the invention are to provide an improved dispensing device of such inexpensive character that it may be thrown away when the contents have been once extruded; to provide a dispensing device wherein a plurality of substances may be retained in separated condition but extruded by a single operation by the user; to provide a device which may be readily sealed and readily unsealed for use; to provide a compact device in sealed condition; to provide a plunger stem which may be retracted to both break the seal and open the extruding passage and to position the said stem ready to extrude the material; to secure simplicity of construction and operation; and to obtain other advantages and results as may be brought out in the following description.

Referring to the accompanying drawing, in which like numerals of reference indicate similar parts throughout the several views;

Figure 1 is an elevation of a dispensing device constructed in accordance with our invention, shown in sealed condition as received by the customer.

Figure 2 is a longitudinal sectional view on line 2—2 of Fig. 1, likewise showing the device in sealed condition;

Figure 3 is a similar sectional view, showing the plunger in position ready to extrude the material;

Figure 4 is a similar sectional view, showing the plunger partly advanced as occurs during extrusion of the material;

Figure 5 is a similar longitudinal sectional view of a modified construction of dispensing device having a single chamber for material; and

Figure 6 is a sectional view of a modified form of sealing means for the extruding end of the device.

In the specific embodiment of the invention illustrated in said drawing, and referring initially to Figures 1 to 4 more especially, the reference numeral 10 indicates the primary container which is preferably of elongated, tubular construction with one end rounded and provided with an extruding orifice 11. At the opposite end of the container is provided a plug or other closure 12 secured in appropriate manner, as by cementing, to the container. This plug is shown as having an outer peripheral rim 13 slightly larger than the inside diameter of the container so as to limit insertion of the plug. At the inner end of the

plug the central portion is cut away providing a recess or pocket 14 thereat for purposes herein-after explained. By virtue of this recess 14, the inner end of the plug constitutes a stop 15.

Within the container is mounted a plunger-head 16 of cork or other suitable material which, when the device is received by the user, is in engagement with the said stop 15 formed at the inner end of the plug. By imparting a longitudinal sliding motion to this plunger head 16 within the container toward the end having the orifice 11, extrusion of the material in the container is obtained. In the particular showing of Figures 2, 3 and 4, an inner container 17 is shown of a diameter such as to substantially fit within the outer or primary container 10 and having a similarly rounded end with an orifice 18 like the primary container. This inner container is of less length than the primary container so as to be slideable therein, and, as received by the user, is in position with its end against stop 15. The plunger head above described fits snugly within this inner container and has an outer end similar to the rounded end of the container so as to ultimately nest therewith for obtaining an extrusion of as much of the contents as possible. In use, the forcing of the plunger outward extrudes material of the inner container into the outer container and extrudes the mixed materials from the outer container.

As a further and important feature of our invention, we provide, as part of the plunger for operating the plunger head, a plunger stem 19. This plunger stem has one end, for convenience designated the inner end, provided with a flaring or other shoulder 20 which will rest against the marginal portion of the rounded end of the primary container about the extruding orifice. Beyond this shoulder 20, the stem provides a reduced portion or neck 21, which in Figures 1 to 5 is shown as somewhat undercut toward the shoulder, and in Figure 6 is shown at 21' as threaded, both of these constructions being for providing means for sealing the orifice and retaining the plunger in position within the container. Where the undercut neck 21 is provided, the seal may be assured by application in fluid condition of a substance 32 which will harden in place, such for example as a cellulose composition. In Figure 6, a cap or nut 33 is shown which is screwed upon the threaded end of the stem outside of the container. In this instance the cap or nut has to be removed before the device is used, and in the other showing, the sealing mate-

rial is broken by twisting or retracting the plunger stem.

The plunger stem extends axially through the container and through a fitting hole in the plug, outside of which it is provided with a suitable finger-piece 22. As here shown, this finger-piece is a disc and the stem is of such length that the disc lies flatwise against the outer end of the plug at such time as the other end of the stem 10 is closing the extruding orifice 11. The instrument therefore has a minimum length for shipping, carrying or storage purposes. The stem likewise passes through the plunger head 16, and in the construction of Figures 2, 3 and 4, passes 15 through the discharge orifice 18 of the inner container 17. Preferably the stem has a fitting engagement in passing through both the orifice 18 and the plunger head 16, but as both of these parts are of a material capable of distortion, the 20 flaring end of the stem approaching shoulder 20 may be pulled through the said parts. Specifically, the container may be of cellulose material, and the plunger head of cork.

It will be noted, that in use of the device, the 25 stem 19 is first drawn out as shown in Figure 3, the relatively light material forming the inner container stretching, bending, cracking or otherwise admitting passage of the flaring end of the stem, and the cork or other material constituting plunger-head 16 likewise stretching or giving 30 so that shoulder 20 is brought into position to underlie the outer end of the plunger head. Re-cess 14 in plug 12 provides the necessary space for the flaring portion of the stem, thereby enabling the plug to be of rigid material and having a fitting engagement with the stem at all times. If found desirable in use, the outer end of the plunger head may be provided with a washer 23 through which the flaring end of the stem may 35 be snapped, but which offers greater resistance to return of the stem therethrough under forward pressure of shoulder 20. This washer is shown in Figures 2, 3 and 4, but for illustrating the possibility of its omission, is not shown in Figure 5.

As one method of assembly, the plug 12, and washer 23 if used, with plunger head 16, are assembled upon stem 19 and with the stem passing through orifice 18 of the inner container 17 but the plunger head not yet introduced into the container. Then the desired material is introduced into said inner container, and the stem slid until the finger piece is flatwise against the outer end of the plug. The inner container is likewise brought against the inner end of said plug. Any material which may have adhered to the protruding part of the stem is then wiped off and a rim of sealing material, such as a cellulose composition 24, is applied around the stem 50 at its point of protrusion from the inner container. This assembled inner unit is then inserted part way into the outer or primary container 10 and that container is then filled through orifice 11, after which the inner assembly is slid 55 completely to place, and sealed at its joints as illustrated at 32 in connection with the extruding orifice, but not restricted to that joint only. In fact, the whole device may be covered with sealing material if desired.

With specific reference to Figure 5, we have shown our invention for use with only a single material, there being no inner container, and the plunger head therefore having a fitting engagement with the inside of the single or primary 75 container 18.

By use of our improved dispensing device, a single material may be conveniently carried and dispensed, or a plurality of materials, normally in separated condition, may be carried and mixed and dispensed when desired for use. While the drawing has represented only one inner container, it will be understood that any number desired may be employed in nesting arrangement. Furthermore, other detail changes and modifications may be made in the construction and use of our improved dispensing device without departing from the spirit or scope of the invention, and we do not wish to be understood as limiting ourselves to the exact details of construction shown or described except as set forth in the following claims when construed in the light of the prior art.

Having thus described the invention, we claim:

1. A dispensing device comprising a container 2 for material to be extruded, means carried within said container for extruding said material, a stem for operating said extruding means, said stem being entirely retractable through said means, and a stop for limiting retraction of said 25 means in a position advanced from the stopping of the retraction of said stem, thereby enabling the stem to be retracted through the extruding means without being permitted to leave the container.

2. A dispensing device comprising a container 30 for material to be extruded, a plunger head slidable within said container for extruding said material, a stem for operating said plunger head, said stem being entirely retractable through said plunger head, and a stop for limiting retraction of said 35 plunger head in a position advanced from the stopping of the retraction of said stem, thereby enabling the stem to be retracted through the plunger head without being permitted to leave the container.

3. A dispensing device comprising a container having a rounded end and a discharge orifice 45 therein for extrusion of material from within the container, a plunger head initially at the opposite end of the container for extruding the material as the plunger is slid toward said orifice, a stem initially passing through said plunger head and entirely retractable therefrom for enabling said plunger head to be operated in one direction 50 only, and a stop for limiting retraction of said plunger head in a position advanced from the stopping of the retraction of said stem, thereby enabling the stem to be retracted through the plunger head without being permitted to leave 55 the container.

4. A dispensing device comprising a container having a discharge orifice in one end for extrusion of material from within the container, a plunger head initially at the opposite end of the 60 container for extruding the material as the plunger is slid toward said orifice, a stem initially extending through said plunger head and closing said orifice and slidable with respect to and entirely retractable from said plunger head for 65 advancing said stem and utilizing the same for advancing the plunger toward the orifice and prevent the stem from retracting said plunger head from an advanced position, and a stop for limiting retraction of said plunger head in a 70 position advanced from the stopping of the retraction of said stem, thereby enabling the stem to be retracted through the plunger head without being permitted to leave the container.

5. A dispensing device comprising in combina- 75

tion with a container, a plunger head, a stem for operating said plunger head, said stem having a shoulder for engaging said plunger head for operating the same in one direction and being movable with respect to the plunger head in the opposite direction whereby the stem cannot retract the plunger head from an advanced position, and a stop for limiting retraction of said plunger head in a position advanced from the 0 stopping of the retraction of said stem, thereby enabling the stem to be retracted through the plunger head without being permitted to leave the container.

6. A dispensing device comprising an elongated 15 container having an orifice therein, a stem within said container, said stem having a shoulder underlying the margin of the container next said orifice and having a threaded terminal neck protruding through said orifice, and a threaded cap 20 applied to said protruding neck and overlying said margin for sealing the orifice and retaining the stem in orifice-closing position.

7. A dispensing device comprising a plurality 25 of nested containers slidable one within another, each container carrying a material to be extruded, and means normally positioned in the extruding ends of said containers and retractable from said ends for providing open extruding orifices in use.

8. A dispensing device comprising a plurality 30 of nested containers slidable one within another, a plunger within the inner one of said containers, and means normally positioned in the extruding ends of said containers and retractable from said 35 ends for providing open extruding orifices in use.

9. A dispensing device comprising a plurality of nested containers slidable one within another each having an end for extruding purposes initially sealed for separating the contents of the several containers, and means normally extending through said extruding ends and retractable therefrom for opening each of said containers whereby the contents may be extruded. 5

10. A dispensing device comprising a plurality 10 of nested containers slidable one within another and initially sealed for separating the contents of the several containers, means for opening each of said containers, and a plunger head within the inner of said containers operable in extruding direction only whereby the material in that container may be extruded to the next and said inner container slid within the next to extrude the material therefrom and retraction of the material into either container is prevented. 15

11. In combination, a container having an orifice at one end and having its other end open, a closure for said open end, a plunger head in said container initially at the end of the container next said closure, a stem passing through said closure and through said plunger head, said stem having an inner enlarged end retractable through said plunger head and functioning both as a closure for said orifice and a stop against complete withdrawal of the stem as well as functioning 25 as a means for advancing the plunger head by 30 a returning inward movement of the stem after retracting the said enlarged end through said plunger head.
